UNITED STATES PATENT OFFICE.

ERWIN KRAMER, OF BERLIN, GERMANY.

FEEDING MECHANISM FOR MILLS.

Application filed November 3, 1925, Serial No. 66,506, and in Germany October 31, 1924.

This invention relates in general to mills, more particularly to eddy mills of the kind described in the copending patent application, Serial No. 735,253. An important factor in continuously-operating mills of this kind is the rate at which the material to be ground is fed into the mill, because the efficiency of the mill depends upon this factor in a high degree. If the mill is not sufficiently filled a considerable quantity of energy is consumed for producing the eddies without a corresponding amount of useful work being done. On the other hand if too much material is fed into the mill, the generation of eddies is interfered with, and the proper colliding of the particles of material against each other prevented.

When the material to be ground has a high specific weight, as in the case of metal, these evils are apt to result in an excessive deposit of metal in the mill and to cause breakages of the driving mechanism, etc.

The power required for driving the eddy mill differs according to the quantity of material fed in, to the size of the granules and to the specific weight of the same. The toughness and other properties of the material also have a considerable effect. It has been found by experiment that the power required as measured at the driving shafts depends on the kind of material treated, the size of its granules and the rate of feed, and that the greatest economy is obtained when the rate of feed is regulated so that the amount of work performed at the driving shafts remains constant.

This object is not accomplished when the ordinary feed devices such as feeding worms, wheels, buckets or the like, that are moved at a constant speed, are employed, unless the material to be ground is carefully sorted before it is introduced into the mill.

In accordance with the present invention the material to be ground is fed into the mill or disintegrator in such a manner that the strength of the torque to be applied to the driven shafts is maintained practically constant.

This is accomplished by controlling the torque at the driving shaft with the aid of the devices hereinafter described and by causing material to be fed into the mill whenever the torque sinks beneath a certain strength until the torque is again increased to normal. The feeding device is then put out of operation and only started

again when the torque sinks to a certain degree. By this means the strength of the torque can be maintained constant within narrow limits. 60

The advantages that accrue from such an arrangement are the following:

The size of the granules of the material to be ground may differ very greatly without necessitating any change of the adjustment of the mill. Furthermore different kinds of material can be fed into the mill without altering the same and mixtures of entirely different kinds of material can be ground in the mill simultaneously. The driving power and capacity of the mill are fully utilized throughout the entire time of operation of the mill and overloading of the same, which results in a reduction of its efficiency and may lead to mechanical injuries of the mill or its power machine, is obviated. 75

When the mill is driven by electric motors the torque applied is measured in terms of the strength of the current consumed by the motor or motors. In the case of a mechanical drive through cogwheels, sprockets, belts or the like, the torque applied is measured by the degree of flexure of an elastic member arranged in the driving mechanism. 80 85

The invention is illustrated by way of example in the drawing in which Figure 1 is a vertical section of the automatic feeding device and a side elevation of the mill and parts of electric motors driving the mill. 90

Figure 2 is a vertical section of the feeding device taken on the line A, B, C, D, E at right angles to the section shown in Figure 1.

Figure 3 shows a longitudinal and a transverse section of a mechanical device for controlling the torque, and Figure 4 shows an electrical torque-controlling device. 95

Referring to Figure 1, the material to be ground is filled into a container or hopper 1 and passes down from the same into a trough 3 which is adapted to be vibrated when necessary to the right and left as indicated by the arrow 54. By this means the material is passed on in proper quantities, i. e. slides from the trough 3 and drops down in the chamber 9 which envelops the trough and then passes through a connecting pipe 11 into the casing 55 of the mill whose shafts 56 and 57 are rotated by the electric motors 58 and 59. The rate at which 100 105 110

- the material is fed into the mill thus depending on the rate of movement of the vibrating trough 3. This trough is supported at its left end by a roll 4. At its other end the trough is provided with an axis 5 that is adapted to be oscillated by an arm 6 pivoted at 8. The two ends of the shaft 8 project from a recess 18 in the sloping wall of the chamber 9 into this chamber, i. e. 10 the middle part of the shaft 8 is located in a second chamber 10 which is integral with the chamber 9. The middle part of the shaft 8 has fixed upon it a forked arm 7 whose prongs engage with a cam 12 fixed on 15 a shaft 13. The shaft 13, which is pivoted in the chamber 10, is rotated continuously by a pulley in any desired manner. Keyed on the shaft 13 is a clutch member 14 whose projecting teeth 15 are adapted to engage 20 with a corresponding number of teeth 16 which project from the cam 12. The cam 12 is arranged to slide to and fro on the shaft 13. A spring 17 normally presses the 25 cam 12 with its teeth 16 away from the clutch member 14, as shown in Figure 2. Whenever the cam 12 is pressed against the coupling member 14 it is rotated by the shaft 13 so as to oscillate the fork 7 and the arm 6 and consequently also the vibrating trough 3, which causes material to drop into the mill as long as it vibrates.
- The shifting of the cam 12 along the shaft 13 can be accomplished in various ways. As 30 shown in Figure 2 an electromagnet 20 may be used for this purpose. When this magnet is energized it attracts its armature 23 which is normally lifted as shown by a spring 24. On the attraction of the armature it swings on its pivot 22 and forces the arm 21 against the cam 12, thus pushing the latter towards the left until its projections 16 engage with the teeth 15 so that it rotates and oscillates the vibrating trough.
- The electromagnet 20 is controlled by a 35 relay or any desirable kind of electromagnetic contact closer whose windings are connected in the circuit of the one electric motor 58 or the other 59. As long as the torque, and hence the current in the motor 40 circuit, has not reached a certain strength, the armature of the relay 38 closes the circuit of the clutch magnet 20, Figure 2, the winding of which is marked 49 in Figure 4. Hence the feeding device 3 operates until 45 the torque of the motor and consequently also the motor current rises to a certain degree. As soon as this happens the relay 50 opens the energizing circuit of the magnet 20, whereupon the armature 23 returns to its normal position so that the arm 21 55 swings towards the right and the springs 17 push the cam 12 out of engagement with the clutch member 14 so as to stop the operation of the trough 3 and the feeding of material into the mill. As the grinding of
- the material proceeds and the ground material passes out of the mill the torque exerted by the motor decreases and this is accompanied by a decrease of the motor current. The relay 38 then releases its armature and 70 the energizing current of the magnet 20 is again switched on to throw on the clutch. The aforescribed events are then repeated, i. e. material is fed into the mill again until the motor current increases to a given 75 strength.
- The arrangement of, and the control effected by, the aforesaid relay are shown diagrammatically in Figure 4. The limbs 39 and 40 of the horse-shoe electromagnet 80 38 are provided with coils 41 and 42 which are connected in the circuit of the motor. A lever 45 pivoted at 44 carries an armature 43 and a contact spring 46. A spring 52 pulls the lever 45 upwards. In this position 85 a current flows from the battery 48 through a conductor 50, the lever 45, the contact spring 46, the contact anvil 47 and thence through the coil 49 of the magnet 20 back to the battery 48. When the magnet 90 38 is energized sufficiently to pull the armature 43 down against the action of the spring 52, the contact spring 46 is removed from the contact anvil 47 and strikes against the stop 51. The current in the coil 49 of the 95 magnet 20 is thus interrupted so that the magnet 20 is deenergized. The arrangement of the clutch may, of course, be modified so that the spring 17 normally presses the cam 12 into engagement with the clutch 100 member 14 and the electromagnet 20 shifts the cam 12 towards the right when it is energized, i. e. it throws the coupling off instead of on. With this arrangement the right hand end of the coil 49 is connected to 105 the contact anvil 51, instead of the anvil 47, and when the magnet 38 is energized sufficiently the armature 43 is attracted and the circuit of the coil 49 is closed, so that the electromagnet 20 disengages the cam 12 from 110 the clutch member 14. Thus, when the strength of the motor current sinks to a certain degree, the electromagnet 38 releases the armature 43 to interrupt the current in the coil 49 and the cam 12 engages with 115 the coupling 14 and the feeding device then feeds material into the mill until the current in the electromagnet 38 rises to such an extent that it again attracts its armature 43.
- Instead of controlling the torque at the shaft of the mill by electrical means, a mechanical controlling means may be used as shown by way of example in the lower part of Figure 2 and in Figure 3. In this 120 driving means a pulley 30 is used for driving the shaft 25 of the mill. Instead of the pulley 30, any other desirable driving member such as a coupling, cogwheel or the like may be used. The pulley 30 is ar- 125

ranged to turn relatively to the shaft 25 on which is keyed a coupling member 26 with projections 27 that are adapted to cooperate with projections 28 fixed to the pulley 30. Between each pair of cooperating projections 27 and 28 is arranged a pressure spring 29. In driving the mill the pulley 30 compresses the spring 29 to a lesser or greater extent according as the shaft 25 offers a greater or lesser resistance. Hence according as the resistance to be overcome, or the torque to be exerted, is small or great, a greater or lesser rotation of the pulley 30 relatively to the shaft 25 takes place. This relative rotary movement is used to effect a lateral displacement of a controlling disk 31. To this end a male screw 32 is fixed to the end of the shaft 25 which is received by a female screw in the disk 31. The disk 31 has a pin 33 which enters into a hole in the hub of the pulley 30, so that the disk 31 rotates with the pulley 30. Whenever the pulley 30 rotates relatively to the shaft 25 the disk 31 is caused to shift to the right or left by the agency of the screw 32. A two-arm lever 35 and 36, which is pivoted at 34, engages at its lower end with a groove in the periphery of the disk 31. As long as the disk 31 revolves without executing any lateral movement the lever 35, 36 remains stationary, but when the disk 31 is shifted towards the right the lever 35 swings to the right and the arm 36 is pressed to the left so that it forces the cam 12 against the coupling member 14 by means of the rod 37. The cam 12 is thus caused to rotate with the shaft 13 and to start the operation of the trough. When the disk 31 returns to its original position the rod 37 shifts to the right to allow the cam 12 to disengage and stop the feeding operation.

When the mechanism is arranged in this manner the elasticity of the springs 29 is made such that at the proper load on the shaft 25 the springs are compressed, while at a smaller load the springs expand and cause the pulley 30 to rotate relatively to the shaft 25 so that the disk 31 is moved laterally. A converse arrangement may, however, be used in which the strength of the springs is such that they expand at the proper load on the shaft 25, while they are compressed when the load is increased. The lateral movement of the disk 31 in the desired direction can be accomplished by providing the male screw 32 with a left-hand or right-hand thread.

In another modification, the projections 27 and 28 may be provided with electrical contacts that are closed or opened when the springs 29 are compressed or expand. The contacts operated in this manner may be used to close or open the circuit of the electromagnet 20. When an arrangement of this kind is employed the lever mechanism

35, 36, 37 can, of course, be dispensed with.

The springs 29 may, of course, be constructed in various ways and many modifications of the entire arrangement are possible. Thus the vibrating trough may be replaced by another kind of feeding device such as worms, feeding wheels and the like.

An advantage of the vibrating trough over these forms of feeding devices is that it is capable of dealing with the most various kinds of materials, and also with fragmentary material whose granules differ very greatly in size, without giving rise to any trouble.

An advantage that accrues from arranging the vibrating trough in the casing 9 (that is, of course, filled with dust) and placing the driving mechanism in a separate chamber 10 is that the driving mechanism operates in a space that is entirely free from dust. By providing the recess 18, through which the shaft 8 extends, the possibility is gained of attaching to this shaft the fork 7 in the chamber 10, while enabling the two shaft ends, that project into the chamber 9, to be attached to the two arms 6 that oscillate the trough 3. In this manner a simple and reliable drive is obtained, while the chambers 9 and 10 are entirely separated from each other. Many variations of this feature of the invention are possible without departing from its scope.

In order to avoid an incessant throwing on and off of the driving mechanism of the feeding device the mill is arranged in practice so that the torque or current strength in the driving motor circuit may decrease by about 10 to 20 per cent of a given value before the feeding mechanism is started. Thus to fully utilize the power of the electric motor or motors the feeding mechanism is started whenever the motor current sinks by 10% beneath its normal strength, while the said mechanism is only stopped again when the motor current rises by 10% above its normal value.

As the torque of the two shafts of the eddy mill are in a high degree dependent on each other, it suffices for the control of the feeding device to measure or determine the torque of one of said shafts only. When the shafts are driven by electric motors the strength of the motor current is a measure of the amount of torque applied to them. According to the kind of motors used the armature current, field current or both are used as a criterion.

I claim:

1. The combination, with a mill having a rotary shaft of the kind described, of a feeding device for introducing material to be ground into the mill, a driving member, an elastic member for transferring the force of said driving member to said rotary shaft while permitting movements of the driv-

- ing member and the rotary shaft relatively to each other, and means for affecting said feeding device at a certain degree of relative movement between said driving member and said rotary shaft.
2. The combination, with a mill having a rotary shaft of the kind described, of a feeding device for introducing material to be ground into the mill, an operating shaft, a coupling for transferring motion from the operating shaft to the feeding device, a driving member, an elastic member for transferring the force of said driving member to said rotary shaft while permitting movements of the driving member and the rotary shaft relatively to each other, and means for affecting said coupling at a certain degree of relative movement between said driving member and said rotary shaft.
3. The combination, with a mill having a rotary shaft of the kind described, of a feeding device for introducing material to be ground into the mill, an operating shaft, a coupling for transferring motion from the operating shaft to the feeding device, a driving member, an elastic member for transferring the force of said driving member to said rotary shaft while permitting rotary movements of the driving member and the rotary shaft relatively to each other, a threaded axially displaceable member that rotates with said driving member, a second threaded member fixed on said rotary shaft, the thread of this member being arranged to cooperate with the thread of said axially displaceable member so that it moves axially with respect to said rotary shaft when said driving member and rotary shaft execute a rotary movement relatively to each other, and means for affecting said coupling whenever said axially displaceable member is displaced to a certain degree.
4. The combination, with a mill having a rotary shaft of the kind described, of a feeding device for introducing material to be ground into the mill, an operating shaft, a coupling for transferring motion from the operating shaft to the feeding device, a driving member, an elastic member for transferring the force of said driving member to said rotary shaft while permitting movements of the driving member and the rotary shaft relatively to each other, means for affecting an electric contact at a certain degree of relative movement between said driving member and said rotary shaft, and an electromagnet for operating said coupling when said electric contact is affected.
5. A mill of the kind described comprising a grinding chamber, a rotary member for moving the material to be ground in said chamber, a rotary shaft for driving said rotary member, an oscillatable feeding chute for introducing material into the grinding chamber, a closed chute-containing chamber, a driving mechanism for said chute, a separate chamber for the driving mechanism adjoining the chute-containing chamber, and a shaft for transferring motion from said driving mechanism to said chute, a part of this shaft being located in the chute-containing chamber and another part being located in said separate chamber.
6. A mill of the kind described comprising a grinding chamber, a rotary member for moving the material to be ground in said chamber, a rotary shaft for driving said rotary member, an oscillatable feeding chute for introducing material into the grinding chamber, a closed chute-containing chamber, a driving mechanism for said chute, a separate chamber for the driving mechanism adjoining the chute-containing chamber, a driving means for applying a torque to said shaft, and means for starting said driving mechanism when said torque decreases to a certain extent and for stopping this mechanism when the torque has increased again to a given strength.
7. A mill of the kind described comprising a grinding chamber, a rotary member for moving the material to be ground in said chamber, a rotary shaft for driving said rotary member, an oscillatable feeding chute for introducing material into the grinding chamber, a closed chute-containing chamber, a driving mechanism for said chute, a separate chamber for the driving mechanism adjoining the chute-containing chamber, a shaft for transferring motion from said driving mechanism to said chute, a part of this shaft being located in the chute-containing chamber and another part being located in said separate chamber, a driving means for applying a torque to said shaft, and means for starting said driving mechanism when said torque decreases to a certain extent and for stopping this mechanism when the torque has increased again to a given strength.

In testimony whereof I affix my signature.
ERWIN KRAMER.
